CLAIM

The ornamental design for a payment notification device, as shown and described.

DESCRIPTION

FIG. 1 is a front view of a payment notification device, showing the new design;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front-right perspective view thereof; and,

FIG. 8 is a rear-left perspective view thereof.

The broken lines shown in FIGS. 2 and 4-8 illustrate portions of the payment notification device that form no part of the claimed design. Any shading and cross-hatching are not features of the design but are utilized to illustrate the surface contours of the payment notification device in the drawings.
